UNITED STATES PATENT OFFICE

FRANZ KRUCKENBERG, OF HEIDELBERG, GERMANY

SECURING RAILS TO HIGH-SPEED SUSPENSION MONORAILWAYS

Application filed March 5, 1927, Serial No. 173,195, and in Germany March 6, 1926.

In high speed suspension mono-railways, operating at speeds of 300 to 400 km/hour, the rail securing means hitherto used for ordinary suspended railways are not usable. It is here necessary to use the open part of the profile to the utmost, to set the rails as exactly as possible in direction and position, to secure completely the running surface against the slightest changes, as well as to ensure a sufficient flexure to the whole running system corresponding to the greater needs of operation. With usual constructions such as supporting carriers or simple side gusset plates for connecting the lateral carrier arms, the desired results cannot be obtained. Supporting carriers make the construction difficult in view of their large space requirements, and also in view of the car running gear height, further owing to the difficulty of allowing a counter wheel running below the rail a sufficient angle of swing, and in particular owing to the particularly unsuitable conditions of flexure. A one-sided jointing of the rail does not provide sufficient security. For with the high dynamic loads caused by the high speeds, it is only possible to prevent lateral bending of the rails from the side connections and therewith disturbance and finally destruction of the running surface, by the use of large quantities of material.

These difficulties are overcome by the present invention, in that it unites, with the smallest space requirements, lowest height and simplest constructional possibilities, a high degree of security of the rail track with the most advantageous possibilities of flexure of the whole running system for operation.

The essence of the invention lies in that the load transmission from the rail to the supporting structure, for example to a lateral carrier holding the rail, is effected by the rail being supported vertically in the plane of the axis of symmetry of the rail cross section. This may be effected by providing a support for the rail which is directly in said plane of symmetry or a support which engages the rail at points or planes on each side of the plane of symmetry. In this way

no bending moment can be exerted on the connecting bolts. For example, with the rail section shown in Figure 1 of the accompanying drawings, the pressure on the rail head *a* of the wheels of the car running thereon is taken by a single support in the plane of the axis of symmetry *b* or by two similar supports in parallel planes *c*, *c'*, one on each side. In this way the most suitable stress conditions are obtained in the securing means of the rail.

In the accompanying drawings which, by way of example, show several methods of securing the rails of high speed suspension mono-railways,

Fig. 1 is an end view of one form of rail,

Figs. 2 and 3 are fragmentary vertical sections through different forms of rail supports,

Fig. 4 is a fragmentary perspective view of a modified form of support,

Fig. 5 is a fragmentary vertical section through another modification,

Figs. 6 and 7 are fragmentary vertical sections on lines O—O and R—R, respectively, of Fig. 8, and

Fig. 8 is a fragmentary plan view of the support shown in Figs. 6 and 7.

Figures 2 to 5 show embodiments in which the rail is supported in the plane of symmetry of the rail head and foot section, while in Figures 6, 7 and 8 an embodiment of the invention is shown in cross section, side view and plan, in which the support of the rail is effected in the planes *c*, *c'* of Figure 1 on each side of the plane of symmetry.

In the arrangement shown in Figure 2 the rail web *d* is deviated sideways (similarly to a key-bit) to such an extent that the web is displaced out of the plane of symmetry. To support the rail in the plane of symmetry a bar *h* engages with wedge faces *e* in the offset portion of the rail web, from the side, so that the surfaces below the rail head bear on the inclined surface *e* on each side of the plane of symmetry. Bolts *f* and a counter plate *g*, which press the rail firmly against the bar *h*, serve to secure the whole. In this way the total pressure acting from above on the rail head is taken by the upper bar sur-

face *e* without the securing bolts having to transmit bending moment.

The bar *h* is mounted on a lateral carrier arm of the supporting framework and is adjustable in the horizontal direction on the carrier arm and can be fixed thereto.

The embodiment shown in Figure 3 has a rail support in the plane of symmetry of the rail section, in which a conical projection *n* on the mounting bar *o* fits from the side into a conical hole *i* formed in the web *l*, provided with strengtheners *k*, *k'* of the rail, and thus receives the load due to the pressure. The rail is secured on the cone *n* by 15 a nut *m* with a washer beneath.

The cone *n* can naturally be replaced by a wedge.

The mounting bar *o* is adjustable and fixably secured on the lateral carrier arm of 20 the supporting framework for the rail track.

In the embodiment according to Figure 4 the support is effected by the trough shaped finger or prongs of the bar engaging in suitable slots in the rail web beneath the rail head, 25 the lower surface of the rail head resting on the upper surface of the finger or prongs. The hollowed finger or prongs *s* of the connecting bar *r* pass through corresponding openings *p* in the rail web *q*, beneath the rail 30 head *t*. The correspondingly formed lower surface of the rail head *t* rests on the prongs. The lower sides of the prongs are so formed that they can be elastically pressed against the head *t* and foot *w* of the rail on each side 35 by clamping plates *u* and through bolts *v*. Should the bolts in this arrangement become ineffective, the rail is prevented from falling off by its being borne on the trough shaped upper surfaces of the prongs *s*.

40 The embodiment shown in Figure 5 has the lateral arm for supporting the rail in the plane of symmetry of the rail section, in the form of a high sided strong metal plate *x*, which engages in a corresponding hole in the rail web, and is welded thereto. The height and cross section of the plate *x* are such that it can transmit the loads occurring. In order to compensate for the weakening of the rail section due to the hole, 45 plates *y*, *y'* can be provided on each side, which are secured to the rail in known manner.

The support of the rail in the plane *c*, *c'* shown in Figures 6, 7 and 8, has a T form 50 outer support *A* which has the stem part *B* passed through an opening in the rail web *D*, and which in combination with two L form inner supports *E*, *E'* takes the load on the rail. The supports, on account of the dynamic loading, are advantageously elastically stressed against the rail. The bolts *F* press the bearing faces of the supports which are sloped off against the correspondingly formed rail profile. By suitably designing the resisting moments of the shanks

of the supports it is easy to distribute the load produced by the weight on the rail among the parts *B*, *E* and *E'* in any desired proportion. Security against disengagement of the rail in the case of loose or broken bolts is provided in a high degree by the T form support *A*. The ends *B*, *G* and *G'* of the supports standing away from the rail are elastically stressed against the rail holder *H*. For this purpose the bearing surfaces thereof are sloped so that when drawn together by the bolts *J* the supports press against the inclined inner surfaces of the flanges of the rail holder. 70 75

The support ends *B*, *G* and *G'* of the supports standing at right angles to the rail are preferably used for horizontal adjustment of the rail. For this purpose the ends *G*, *G'* are provided with large elongated holes *K*, in which fit the lateral wings *L* of adjusting plates *M*. The adjusting plates have holes *N* formed in the wings, in which holes the securing bolts *J* accurately fit. The holes are naturally located at different points in different sets of plates, so that a suitable set is available for each rail adjustment. In this way the supports can be secured by the bolts correctly adjusted in any particular case. 80 85 90

It is to be noted that although the contact of the rail with its support is in planes *c*, *c'* (Fig. 1), these planes are spaced equidistant from and on each side of plane *b* and therefore the resultant support is actually in plane *b*. 95

What I claim is:—

1. A securing arrangement for the rails of high speed suspension mono-railways with upper and lower rail running faces and of the type including rail supporting members and means for securing the rails to said supporting members, characterized in that the wheel loads are transmitted directly from the rail to the rail supporting members in the plane of symmetry of the rail head and foot cross section. 105 110

2. A securing arrangement according to claim 1 characterized by the fact that the direct contact between the rail and the supporting members occurs in two planes 115 parallel with and equally spaced from the plane of symmetry of the rail cross section.

3. A securing arrangement according to claim 1, characterized in that the supporting members of the rail comprise wedge shaped members which are pressed between and into engagement with the head and the base of the rail to provide a support in the plane of symmetry of the rail section, and said members being elastically stressed against the rail. 120 125

4. A securing arrangement according to claim 1, characterized in that a rail supporting member extends through an opening in the rail web and is adjustably mounted on, 130

and fixable to, the lateral carrier arm of the supporting framework.

5. A securing arrangement according to claim 1, characterized in that the securing members consist of a **T** form outer support of which the tail passes through the rail web, and two **L** form inner supports, which are elastically stressed against the rail.

10 6. A securing arrangement as set forth in claim 1, in combination with fixed supports upon which said supporting members are adjustably mounted to permit adjustment of the position of the rail.

15 7. A securing arrangement as set forth in claim 1, in combination with fixed supports upon which said supporting members are adjustably mounted to permit adjustment of the position of the rail, the cooperating surfaces of said members and said fixed supports permitting the said members to be elastically stressed against said supports when secured thereto in the desired position of adjustment.

20 In testimony whereof I have signed my name to this specification.
